CLAIM

The ornamental design for an applicator cap as shown and described.

DESCRIPTION

FIG. 1 is a top perspective view of an applicator cap in accordance with a first embodiment;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded perspective view of an applicator cap in accordance with a second embodiment, in a state of use. The broken lines in FIGS. 1–8 depict portions of the applicator cap that form no part of the claimed design. The broken lines shown in FIG. 9 depict environmental subject matter and form no part of the claimed design.

1 Claim, 9 Drawing Sheets
